Patented Sept. 20, 1921.

UNITED STATES PATENT OFFICE.

WILLIAM F. KIESEL, JR., OF ALTOONA, PENNSYLVANIA.

RATCHET-WRENCH.

1,391,636.

Specification of Letters Patent. Patented Sept. 20, 1921.

Application filed May 17, 1921. Serial No. 470,381.

To all whom it may concern:

Be it known that I, WILLIAM F. KIESEL, Jr., a citizen of the United States, and residing at Altoona, Blair county, State of Pennsylvania, have invented certain new and useful Improvements in Ratchet-Wrenches, of which the following is a specification.

This invention relates to ratchet wrenches and particularly to wrenches of this type designed for performing heavy duties, such as opening the drop bottom doors of freight cars loaded with coal or similar material.

The object of the invention is to provide a wrench of this class which combines simplicity with effectiveness and strength so that it is easy to operate and comparatively inexpensive to manufacture and also thoroughly efficient.

A wrench made in accordance with this invention is illustrated in the accompanying drawings in which:

Figure 1 is a plan view of the wrench;

Fig. 2 is a side view of the same; and

Fig. 3 is a section on line 3—3 of Fig. 1.

The wrench comprises only four parts, the work engaging ratchet 10, the handle 11, the housing 12 which rotatably supports the ratchet, and a rivet 13 which extends through the housing and the handle and pivotally secures them together.

The ratchet wheel 10 has trunnions 10' concentric with its toothed periphery and a central opening 10² which may be square or which may have other polygonal form. The trunnions extend into aligned apertures in the legs of the U-shaped housing 12 and the ratchet wheel is rotatably supported thereby in this housing.

The handle may be of any desired length depending upon the use to which the wrench is to be put and the work to be done and is preferably of I-beam shape in cross section, as shown in Fig. 2. The inner end of this handle extends laterally and terminates in a point 11' which constitutes a pawl adapted to coat with the teeth of ratchet wheel 10. The U-shaped housing 12 has its ends 12' inturned as shown in Fig. 1 and these inturned ends are adapted to oscillate between

the side flanges 11² of the handle so that the handle and housing have only a limited relative movement around the rivet 13.

In operation the wrench is placed in position with the member to be turned extending through the opening 10², and the handle operated to effect the turning movement. It will be obvious that if the handle is moved in one direction the tooth 11' will engage one of the teeth of the ratchet wheel and effective work will be done on the member to be rotated, while movement in the opposite direction will disengage the pawl 11' from the ratchet wheel and will cause the upper flanges 11² (Fig. 2) to strike the inturned toes 12' of the housing so that the handle and housing rotate together about the ratchet wheel into a position where the pawl 11' may engage a new tooth.

A feature of the invention resides in the formation of the housing member in one piece and in inturning its ends. The number of parts is thereby reduced to a minimum and the parts remaining are of very simple design and present a maximum strength for a given weight of metal used.

Having thus described the invention what I claim as new and desire to secure by Letters Patent is:

A ratchet wheel of the class described, comprising in combination, a work engaging ratchet member, a handle having an end comprising a pawl for engaging the said ratchet member and having an abutment, and a U-shaped housing pivotally attached to the handle and rotatably supporting the ratchet member, said housing having its ends inturned toward the handle and adapted to strike the abutment on the handle when the handle is moved in one direction to cause the handle and housing to move together, the pawl being disengaged from the ratchet upon movement of the handle in this direction and engaging the ratchet upon movement in the opposite direction.

In testimony whereof I hereunto affix my signature.

WILLIAM F. KIESEL, JR.
